CLAIM

An ornamental design for a hanger for rain gutters, as shown and described.

DESCRIPTION

FIG. 1 is a perspective view of a hanger for rain gutters; FIG. 2 is another perspective view of the hanger for rain gutters of FIG. 1;

FIG. 3 is a front elevation view of the hanger for rain gutters of FIG. 1;

FIG. 4 is a rear elevation view of the hanger for rain gutters of FIG. 1;

FIG. 5 is a left-side elevation view of the hanger for rain gutters of FIG. 1;

FIG. 6 is a right-side elevation view of the hanger for rain gutters of FIG. 1;

FIG. 7 is a top plan view of the hanger for rain gutters of FIG. 1; and,

FIG. 8 is a bottom plan view of the hanger for rain gutters of FIG. 1.
